UNITED STATES PATENT OFFICE.

GEORGE EMMERT, OF CORPUS CHRISTI, TEXAS.

LAMP-CHIMNEY HOLDER.

1,178,845.

Specification of Letters Patent. Patented Apr. 11, 1916.

Application filed August 13, 1915. Serial No. 45,330.

To all whom it may concern:

Be it known that I, GEORGE EMMERT, a citizen of the United States, residing at Corpus Christi, in the county of Nueces and State of Texas, have invented a new and useful Lamp-Chimney Holder; and I do hereby declare the following to be a full, clear, and exact description of the invention, such as will enable others skilled in the art to which it appertains to make and use the same.

This invention relates to an improved lamp chimney holder, and an object of the invention is to provide a hinged member carried by the lamp, and to which the chimney is connected, so that the hinged member may be swung upon its hinge connection and the chimney with the same, for lighting the wick and extinguishing the light, instead of raising or removing the chimney entirely for such purpose.

Another object of the invention is to provide yieldable means for holding the chimney to the hinged member, said yieldable means including rods, which conform to the contour of the chimney, and have laterally extending arms provided with curved ends, only the edges of which bear against the wall of the chimney, to prevent the rod from contacting with the chimney, which rod being harder to heat after lighting the lamp, will tend to otherwise crack the chimney.

A further object of the invention is the provision of a plurality of yieldable coil springs connecting the lower ends of the rods and the hinged member.

In practical fields of construction may necessitate alterations, falling within the scope of what is claimed.

40 The invention comprises further features and combination of parts, as hereinafter set forth, shown in the drawings and claimed.

In the drawings:—Figure 1 is a view in side elevation of a portion of the body of the lamp showing the holding means for the chimney. Fig. 2 is a vertical sectional view. Fig. 3 is a detail view of one of the rods. Fig. 4 is a view of a modified form, in which the hinged member has upwardly extending lugs to receive screws to engage above a rib at the lower portion of the chimney.

45 Fig. 5 is a view of another modified form of the invention, in which the hinged member has two annularly extending flanges, to 50 the outer one of which the chimney has a

threaded connection. Fig. 6 is an enlarged detail view of a hinge connection between the ring 3 and the flange 2. Fig. 7 is a sectional view on line 7—7 of Fig. 6. Fig. 8 is a sectional view on line 8—8 of Fig. 6. 60

Referring to the drawings, 1 designates a portion of the upper part of the body of the lamp, to a flange 2 of which the annular ring 3 (angular in cross section) is hinged at 4. The lamp chimney 5 rests upon the ring 3, 65 and is held concentric therewith by the upwardly extending lugs 6. The ring 3 opposite the hinge 4 is provided with a downwardly extending spring lug 7, the curved portion 8 of which engages the edge of the flange 2, to hold the ring in place, as shown in Fig. 1. A small knob 9 is carried by the lug 7, whereby the same may be pressed or moved slightly outwardly, to release the ring. Rods 10 (which are of a shape corresponding to the contour of the chimney) are arranged upon diametrically opposite sides of the chimney, and have hooks 11 at their upper ends to engage between any two diametrically opposite corrugations 12 of the upper edge portion of the chimney. The lower end of each rod has connected to it three coil springs 13, 14 and 15. The coil spring 13 exerts a direct downward pull upon its respective rod, whereas the coil springs 14 and 15 exert downward and lateral pulls. The lower ends of the springs 13, 14 and 15 upon each corresponding opposite side of the ring connect to three of the lugs 6, thereby holding the chimney yieldably on the ring 3. The springs 14 and 15 prevent undue tilting of the chimney with respect to the ring. Each rod 10 is provided with laterally extending arms 16, the end portions of which are curved inwardly toward the outer surface of the chimney, as shown at 17, and the edges 18 of the inwardly extending part 17 are provided with asbestos 19, to bear against the outer surface of the lamp chimney, thereby preventing 100 the cold metal of the rod from contacting with the glass. 95

In Fig. 4 the ring 3 is provided with four lugs 6^a only, which receive threaded thumb screws 20, which engage the chimney base immediately above the rib 21 thereof, thereby holding the chimney to the ring 3. 105

In Fig. 5 the ring 3^a is U-shaped in cross section, the inner flange 22 of which engaging the interior surface of the base of the 110

chimney, whereas the outer flange 23 is threaded to the base of the chimney, thereby connecting the chimney to the ring 3^a.

The hinge connection 4 comprises the extension 4^a extending from the flange 2 bent at 4^b, and immediately beyond the bend formed into a semi-circular curved part 4^c, and then extending upwardly and angularly and bent again upon itself at 4^d, then downwardly and angularly and about the bend 4^b as shown at 4^e, and in contact with the part 4^a. Immediately before the bend 4^e is made a semi-circular curved part similar to 4^c is constructed and designated by the numeral 4^g, and in the semi-circular parts (which are in registration) a pin 4^h is mounted. The extension 4^k of the ring 3 has sleeve bearings 4^m mounted upon the pin 4^h. It will be observed that when swinging the ring 3 upon its hinge 4, the extension 4^k will contact with the upwardly and angularly extending extension part of the extension 4^a, thereby limiting the ring in its movement.

The invention having been set forth, what is claimed as new and useful is:—

1. In combination, a lamp body having a flange at its upper part, a ring hinged thereto and having a latch opposite the hinge to engage the flange, said ring having upwardly extending lugs and designed to receive the chimney, a pair of diametrically oppositely disposed rods conforming to the contour of the chimney having hooks at their

upper ends to engage the upper edge portion of the chimney, the lower end of each rod having three coil springs, connected to three of the lugs of the ring, one spring exerting a direct downward pull on the rod, the other two springs exerting downward and lateral pulls.

2. In combination, a lamp body having a flange at its upper part, a ring hinged thereto and having a latch opposite the hinge to engage the flange, said ring having upwardly extending lugs and designed to receive the chimney, a pair of diametrically oppositely disposed rods conforming to the contour of the chimney having hooks at their upper ends to engage the upper edge portion of the chimney, the lower end of each rod having three coil springs, connected to three of the lugs of the ring, one spring exerting a direct downward pull on the rod, the other two springs exerting downward and lateral pulls, each rod having laterally extending arms, the ends of which being curved inwardly toward the chimney and having asbestos parts to engage the chimney.

In testimony whereof I have signed my name to this specification in the presence of two subscribing witnesses.

GEORGE EMMERT.
